LAMP TABLE OR PEDESTAL

Simon V. Waitzman, 195 Hicks St.,
Brooklyn, N.Y. 11201

Filed May 9, 1973, Ser. No. 358,717

Term of patent 14 years

Int. Cl. D6—03

U.S. Cl. D6—175

FIG. 1

FIG. 2

FIG. 3

FIG. 5

FIG. 6

FIG. 7

FIG. 1 is a view in perspective of a lamp table or pedestal showing my new design;

FIG. 2 is an end elevational view thereof;

FIG. 3 is a side elevational view thereof;

FIG. 4 is a top plan view thereof;

FIG. 5 is a perspective view of a lamp table or pedestal showing a modified form of my new design;

FIG. 6 is an end elevational view thereof; and

FIG. 7 is a side elevational view.

I claim:

The ornamental design for a lamp table or pedestal, substantially as shown and described.
